UNITED STATES PATENT OFFICE.

CLAUDE G. BEWLEY, OF SPOKANE, WASHINGTON, ASSIGNOR TO SPOKANE CONCRETE FLOWER POT MACHINE CO., INC., A WASHINGTON CORPORATION.

TAMPING MECHANISM.

1,278,835.

Specification of Letters Patent. Patented Sept. 17, 1918.

Application filed February 25, 1918. Serial No. 219,017.

To all whom it may concern:

Be it known that I, CLAUDE G. BEWLEY, a citizen of the United States, residing at Spokane, in the county of Spokane and State 5 of Washington, have invented new and useful Improvements in Tamping Mechanism, of which the following is a specification.

This invention relates to improvements in tamping mechanism, and has to do more 10 particularly with tamping mechanism especially adapted for molding machines.

My invention is particularly adapted for molding machines for making concrete flower pots in which the concrete is delivered 15 between male and female molds, one of which rotates. As used on my present machine, my improved mechanism includes a tamper adapted to extend between the molds to tamp the concrete as the product is being 20 formed. The tamper is given a reciprocating movement and the novel arrangement is such that as the product advances toward completion, the tamper recedes during its reciprocating movement, by reason of its tamping 25 contact with the gradually advancing fill, so that the concrete is uniformly packed irrespective of variation of the wall of the product. Further, the tamper is capable of being manually retracted or advanced from 30 or toward the material and is always ready for instant operation after adjustment.

In molding flower pots, and many other kinds of product, the walls not only vary in 35 their inclination from the vertical, as regards different sizes and shapes, but the products call for adjustment as regards their difference in diameter, some requiring molds of relatively large, and others requiring molds of relatively small diameter or size. 40 Thus my invention provides for adjustment of the tamper both as regards its angular disposition, and to its radial adjustment with respect to the axis of rotation of the molds or mold. In this connection, it is a special 45 feature of my invention to provide means whereby either or both characters of adjustment may be readily made without disconnecting the operative connection between the tamper and its driving shaft.

50 My invention has many other features which will be more fully described in connection with the accompanying drawing and which will be more particularly pointed out in and by the appended claims.

In the drawing:—
55 Figure 1 is a view in side elevation, with parts in section, showing one form of my improved tamping mechanism.

Fig. 2 is a plan view thereof.
60 Like characters of reference designate similar parts throughout the different figures of the drawing.

As illustrated, 1, designates a portion of the main frame of the molding machine which is shown provided with an adjusting 65 slot 2. In this specific form, the invention is shown applied to a machine for making concrete flower pots and the female mold is indicated at 3, and is rotatable, while the male mold is indicated at 4, and is movable 70 into and out of the female mold, as illustrated in my patented machine. Suitable feeding mechanism, such for instance as shown in my pending application filed Feb. 9, 1918, Serial No. 216,245, is provided for 75 delivering the concrete to the space between the molds.

As the molding operation proceeds, it is necessary to tamp the concrete as the latter is delivered, and therefore my invention includes a tamper 5, which may be a flat strip of any suitable material, and of the required thickness to operate between the molds, preferably by being reciprocated.

I will next describe an improved cross head 85 structure which serves to hold the tamper and by means, or through which movement is imparted to the tamper, the cross head being provided with a novel construction whereby the tamper is allowed to re- 90 cede as the product advances toward completion.

My improved cross head structure is designated at 6, and the same is provided with a flat tamper abutting face 7, against which 95 the tamper 5 rests. A flat spring 8, centrally bowed at 9, has ends 10, which bear against the tamper 5, and the spring has flanges 11, which engage opposite sides of a yoke 12, whereby the spring is held in the 100 position shown. A tension screw 13, having a lock nut 14, serves to retain the spring under the desired tension whereby longitudinal movement of the tamper with respect to the cross head will be resisted sufficiently to only 105 permit of longitudinal adjustment of the tamper except when considerable endwise thrust is applied thereto. However, it is a

feature of my invention to limit movement of the tamper 5, as regards adjustment and as regards reciprocation, to a straight linear movement. This is accomplished by the side walls of the yoke 12, which serve to hold the tamper against anything except endwise movement.

My improved cross head is laterally grooved, as shown at 15, and guides 17 project into said grooves to permit the cross head to reciprocate on said guides. The guides may be connected, as by a bar 18, to maintain the guides in line, and the said guides are also provided with lugs 19, for pivotal connection with an adjusting frame which I am now about to describe. It will now be seen that by reason of this pivotal adjustment, the tamper may be tilted to any desired angular position either from or toward the vertical, or into a vertical position.

The cross head is provided with a socket head, indicated at 20, and which is provided with a cavity into which oppositely acting socket members 21 and 22 are slidably mounted. Each socket member may be case hardened, for engagement with a pitman ball 23. Each socket member is adjusted by means of an adjusting screw 24 and 25, the same having lock nuts 26 and 27. Thus a firm operative ball and socket connection is effected.

I will next describe the adjusting frame whereby bodily adjustment of the tamper, toward or away from the axis of rotation of the molds is effected, in accordance with the size of mold employed, that is, the diameter of molds employed.

The base of the frame is indicated at 28 and is linearly slidable into various positions of adjustment on the main-frame 1. Bolts 29, extending through the base 28, and the slot 2, serve to hold the frame in adjusted positions toward or from the molds 3 and 4. Journaled in said adjusting frame is a driven shaft 30, which is rotatable in a bearing 31 but which is held against longitudinal movement therein by a collar 32, on one side of the bearing and the hub 33, on the other side of the bearing. Hub 33, is part of a crank member which is shown in the form of a disk 34. Crank disk 34 has a cavity 35 wherein is disposed a pair of oppositely acting socket members 36 and 37, between which is interposed a ball 38, of a pitman 39. A wedge 40, or any suitable adjusting device may serve to advance and hold socket member 37 into engagement with ball 38. An adjusting screw 41 and a lock nut 42, may serve to advance and hold socket member 36, in working engagement with ball 38. These socket members will also be case hardened. Thus pitman 39,

forms transmitting means for transmitting rotary motion from the disk 34 to reciprocate the cross head 6.

It will be clear that in making flower pots, many different sizes may have walls of the same slope, and in that event, the pivotal adjustment would not have to be used after the tamper had once been accurately adjusted. However, the advantage of my construction lies in the fact that irrespective as to whether or not the pivotal adjustment is used, bodily adjustment made by the frame does not require altering of the pivotal adjustment, and in case both are necessary, they are present.

By reason of the operative connection of the cross head with the driven shaft, any pivotal adjustment necessary may be made without disturbing or requiring any alteration of the driving connection between the cross head and the crank disk.

It is believed that the novelty and utility of my invention will be fully understood from the foregoing description, and while I have herein shown and described one specific form of my invention, I do not wish to be limited thereto except for such limitations as the claims may import.

I claim:—

1. In a tamping mechanism for machines for molding concrete flower pots, a tamper adapted to extend between the molds for engagement with the concrete as it is being molded to form the wall of the pot, mechanism for imparting tamping movement to said tamper, and a device for adjusting said mechanism to dispose the tamper at an angle corresponding to pot walls of different sizes.

2. In a tamping mechanism for molding machines, a tamper, an adjustable frame, a guide pivoted on said frame for adjustment to different angular positions, a cross head 105 slideable on said guide and connected with said tamper, a driven shaft journaled in said frame, and means for reciprocating said cross head from said shaft.

3. In a tamping mechanism for molding machines, a tamper, and adjustable frame, a guide pivoted on said frame for adjustment to different angular positions, a cross head slideable on said guide and connected with said tamper, a driven shaft journaled 110 in said frame, a crank member on said shaft, and a pitman rod having a ball and socket connection with said crank member and a ball and socket connection with said cross head.

In testimony that I claim the foregoing as my own I hereby affix my signature.

CLAUDE G. BEWLEY.
